UNITED STATES PATENT OFFICE.

CHARLES N. HARE, OF BOWLING GREEN, OHIO.

VALVED PISTON.

SPECIFICATION forming part of Letters Patent No. 658,912, dated October 2, 1900.

Application filed May 17, 1900. Serial No. 16,980. (No model.)

To all whom it may concern:

Be it known that I, CHARLES N. HARE, a citizen of the United States, residing at Bowling Green, in the county of Wood and State 5 of Ohio, have invented certain new and useful Improvements in Valved Pistons; and I do declare the following to be a full, clear, and exact description of the invention, such as will enable others skilled in the art to which it applies to make and use the same, reference being had to the accompanying drawings, and to the figures of reference marked thereon, which form a part of this specification.

In pumping oil-wells and other deep wells 15 it is extremely difficult to secure the "suckers" upon the plunger of the valved piston, commonly called the "working valve," against becoming accidentally loosened and lost in the bottom of the well. This is largely 20 due to the great resistance and pressure encountered at great depths. In pumping such a well when the parts which are requisite in constructing the valved piston become disarranged it usually entails great labor, loss of 25 time, and expense, and it is frequently necessary to remove the tubing from the well in order to recover the lost parts and permit resumption of the operation of the well.

In the accompanying drawings, in which 30 Figure 1 is a central vertical sectional elevation of my device and Fig. 2 a perspective view of the locking device hereinafter referred to, is illustrated a valved piston of approved construction and which is in general use in 35 the oil fields. This valved piston is made up of an open chambered piece 1, containing a ball 2, serving as a valve, resting upon removable seat 3. The chambered valve-piece 1 at bottom is screwed upon a tubular piece 4, 40 upon which are slipped a series of leather buckets, washers, or suckers 5, between which are interposed collars 6. The two series of pieces 5, 6 are now secured in place by means of an internally-threaded sleeve 7, 45 screwed upon the exteriorly-threaded portion of the sleeve 4 at bottom. When the sleeve 7 is tightly screwed in place, all of the parts are rigidly held in assembled relation. Formed integral with the sleeve 7 is a downwardly-projecting loop 8, which is used in screwing the sleeve 7 firmly in place.

The device thus far described is found to

serve its purpose admirably; but should the lower threaded sleeve 7 become loosened from its place it will be seen that all of the pieces 55 5 and 6 will slip down and off of the tube 4, thus interfering with the stroke of the plunger and with the flow of the oil or water.

My invention relates to and its object is to provide means for overcoming the difficulty 60 here indicated, and more particularly to furnish a cheap, simple, durable, and efficient means for detachably securing the threaded sleeve 7, above referred to, in place in such fashion that it cannot become accidentally 65 displaced. I attain these objects as follows: 9 is a cotter having at one end a lug 10 and at its other end a detent 11. This cotter is formed of resilient metal and is made sufficiently thin to serve as a spring. Through 70 the tube 4 is an orifice 12. Extending downwardly from the orifice 12 is a groove 12^a, which at its lower end is deepened to form a slot 12^b through the wall of the tube 4. In the flat bottom face of the sleeve 7 is a series 75 of notches 13, extending radially from the bore of the sleeve. These notches are of sufficient width and depth to receive the detent 11. The piece 9 is laid into the groove 12^a, with the lug 10 resting in the orifice 12 and 80 with the detent 11 at the lower end of the piece 9 projecting outwardly. The pieces 5 and 6 may now be slipped into place over the tube 4. The piece 9 rests in its channel or groove in such manner that it will not interfere with the passage of the pieces 5 and 6 except at bottom, where the detent 11 projects beyond the circumferential circle of the tubular piece 4. The detent can, however, be sprung inwardly in its slot to permit the upward passage of the pieces 5 and 6. 85 When all of the pieces 5 and 6 have been assembled as shown, the bottom sleeve 7 is screwed home, while the detent 11 is pressed inwardly in its slot, the upper part of the 90 cotter being rigidly held by one or more of the encircling sleeves 6. Upon the detent 13 being now allowed to spring outwardly into normal position it engages one of the notches 13, and thus the sleeve is prevented from becoming unscrewed. If for any purpose it becomes necessary to remove either of the parts 5 or 6, this may be readily accomplished by 95 pressing inwardly the end of the piece 9, thus 100

disengaging the detent 11 from the notch 13, into which it has fallen. This will permit the unscrewing of the sleeve 7 and the removal of the parts 5 and 6.

5 Having described my invention, what I claim, and desire to secure by Letters Patent, is—

In a valved piston for oil-wells, a valve-carrying tube, a series of buckets or suckers alternating with a series of metal sleeves on said tube, a screw-threaded portion at the bottom of said tube, a screw-threaded sleeve

thereon, a spring-cotter having a detent at its lower end, normally in engagement with said screw-threaded sleeve and secured at its upper end by one or more of said alternating metal sleeves.

In testimony whereof I affix my signature in presence of two witnesses.

CHARLES N. HARE.
